UNITED STATES PATENT OFFICE.

THOMAS DROST, OF ELMHURST, NEW YORK, ASSIGNOR TO THE BRUNSWICK-BALKE-COLLENDER COMPANY, OF CHICAGO, ILLINOIS, A CORPORATION OF DELAWARE.

CUE RACK.

Application filed November 15, 1920. Serial No. 424,022.

To all whom it may concern:

Be it known that I, THOMAS DROST, a citizen of the United States, residing at 66 Corinth Ave, Elmhurst, in the county of 5 Queens and State of New York, have invented certain new and useful Improvements in Cue Racks, of which the following is a specification.

This invention relates to racks for holding 10 cues used in playing billiards and pocket billiards and its primary object is to provide a simple and efficient device which will permit cues to be easily inserted and withdrawn therefrom without injury to the cues 15 and which will hold the cues securely in an upright position.

Other objects and advantages of my invention will be apparent as it is better understood by reference to the following specification in connection with the accompanying drawing disclosing a selected embodiment thereof in which,

Figure 1 is a front elevation of a cue rack embodying my invention.

Figure 2 is a horizontal section on line 2—2 of Fig. 1.

Figure 3 is a vertical section on line 3—3 of Fig. 2.

Figure 4 is a view of the rear edge of the 30 holder looking in the direction of the arrows 4—4.

Figure 5 is a horizontal section of a modified form of the invention.

Referring to the drawings, a frame 6 of 35 suitable form is intended to be secured in an upright position to wall or other support and it is provided with a base 7 having sockets 7' to receive the butts of the cues 8. A cue holder 9 is secured between the sides 40 10 of the frame and is provided with recesses 11 along one edge in alignment with the sockets in the base to receive the upper portions of the cues.

The cue holder comprises an upper member 12 and a lower member 13 which are secured together one upon the other along their rear edge portions by screws 14 or other suitable means. The recesses 11 are formed between forwardly projecting and 50 aligning projections 12' and 13' on the holder members. A roller 17 is disposed in the horizontal slot 15 between each pair of projections, and each roller projects laterally beyond the projections into the recesses 55 on each side thereof. The rollers 17 are

pivotal mounted on the upwardly projecting front ends 16 of the spring arms 18 which are preferably made of round spring wire and extend rearwardly in the slots 15, pass between the contacting rear portions of the upper and lower members 12 and 13 respectively in grooves 19, then extend downwardly in grooves 20 in the rear edge of the lower member 13, and have their rear ends 21 bent forwardly and seated in the inclined recesses 22. The frame 6 may be provided with a rear wall 23 abutting the rear edge of the cue holder 9 and serving to retain the spring arms 18 in the holder, but the spring arms may be secured in place by pins or 60 nails 24 in the manner shown in Figs. 2 and 3 especially when the rear wall is omitted. Each roller 17 is preferably mounted midway between adjacent recesses 11 and projects into each of said recesses to cooperate 65 with the next roller on each side thereof. The opposing peripheral faces of the cooperating rollers are spaced apart a distance 70 less than the diameter of the cues at the point of engagement thus providing a narrow passage through which the cues must be forced. The spring arms 18 are secured only at their rear end portions and are free 75 to bend laterally in the slot 15 to permit the rollers to yield when a cue is inserted or withdrawn from the recess. The pivotal engagement of the roller upon the end of the spring arm permits the roller to rotate, and thus facilitates the insertion and withdrawal of the cue. The rear portions of the 80 upper member 12 are cut away at 12" adjacent each of the spring arms 18 to permit greater freedom of motion of these arms. The spring arms may be connected in pairs as shown in Fig. 5 in which arms 31 and 85 32 are connected by a transverse part 27 which is seated in a groove 28 in the lower member 29.

It has generally been customary in racks of this type where rollers were used to retain 90 cues within the recesses to provide a pair of rollers for each recess and the rollers in one recess had no cooperative action with the rollers in any other recess.

My invention greatly simplifies the construction of this type of cue racks, and provides rollers of relatively large diameter 105 which project into adjacent recesses for operative engagement with cues introduced therein. The two rollers projecting into 110

each recess will readily yield sufficiently to permit the insertion of a cue and they will retain the cue in upright position in the rack until forced apart to permit its withdrawal. 5 This construction reduces the number of parts, enables the capacity of the rack to be increased and thereby reduces the cost of manufacture.

I am aware that the holder 9 may be 10 reversed in position in the rack and that other changes in construction and in arrangement of parts may be made without departing from the invention and I reserve the right to make all such changes as fairly fall within 15 the scope of the following claims.

I claim:

1. A cue rack comprising a holder having a plurality of spaced recesses to receive the cues, and a cue engaging means yieldingly 20 mounted in said holder between and projecting into each pair of said recesses to co-act with the corresponding means on either side thereof to hold the cues in the recesses and bodily movable laterally to permit the 25 insertion and removal of the cues.

2. A cue rack comprising a holder having a plurality of spaced recesses to receive the cues, and a roller yieldingly mounted in said holder between and projecting into each pair 30 of said recesses to co-act with the rollers on either side thereof to hold the cues in the recesses and bodily movable laterally to permit the insertion and removal of the cues.

3. A cue rack comprising a holder having a plurality of spaced recesses along one edge thereof to receive the cues, a spring arm mounted in said holder between each pair of recesses, and cue retaining means mounted on each of said arms, each of said cue retaining means projecting into the recess on each side of the arm and co-acting with the corresponding means on the adjacent arm on either side thereof to yieldingly retain the cues in said recesses.

4. A cue rack comprising a holder having a plurality of spaced recesses along one edge thereof connected by a slot extending longitudinally of said edge, a spring arm mounted in said slot between each pair of said recesses, and a roller pivotally mounted on each of said arms and movable therewith longitudinally of said slot, each of said rollers projecting into the recess on either side thereof to yieldingly retain the cues in said recesses.

5. A cue rack comprising a holder having a plurality of spaced recesses along one edge thereof connected by a slot extending longitudinally of said edge, an arm of spring wire secured in said slot between each pair of said recesses, and a roller pivotally mounted on the free end of each of said arms and yieldingly movable longitudinally of said slot, each of said rollers projecting into the recess on either side thereof and

co-acting with the opposing roller therein to yieldingly retain the cues in said rack.

6. A cue rack comprising a holder composed of an upper and a lower member provided with oppositely disposed spaced recesses along one edge thereof to receive the cues, the recessed portions of said members being spaced to form a longitudinal slot in said edge communicating with said recesses, and a means movable longitudinally in said slot and projecting into adjacent recesses to yieldingly retain the cues in said recesses and movable bodily laterally to permit the insertion and removal of the cues. 75

7. A cue rack comprising a holder composed of an upper and a lower member secured together along their rear edges and having oppositely disposed spaced recesses along their front edges to receive the cues, the recessed portions of said members being spaced to form a longitudinal slot therebetween communicating with said recesses, and rollers yieldingly mounted in said holder and projecting into adjacent recesses and movable longitudinally in the slot to permit the insertion and removal of cues and to yieldingly retain them in said recesses. 80

8. A cue rack comprising a holder composed of an upper and a lower member secured together along their rear edges and having oppositely disposed recesses along their front edges to receive the cues, the recessed portions of said members being spaced to form a longitudinal slot therebetween communicating with said recesses, a plurality of spaced spring arms each secured at one end in said lower member and having its free end yieldingly movable longitudinally of said slot, and means on the free end of said arms and projecting into adjacent recesses to retain the cues in said recesses. 95

9. A cue rack comprising a holder having a plurality of spaced recesses to receive the cues, a spring arm arranged in said holder between each pair of said recesses and having an upwardly projecting end, and a roller mounted on said upwardly projecting end of the spring arm between and projecting into said recesses to co-act with the rollers on either side thereof to hold the cues in said recesses. 100

10. A cue rack comprising a holder having a plurality of spaced recesses to receive the cues, an arm arranged in said holder between said recesses, a roller mounted on said arm and projecting into said recesses to co-act with adjacent rollers to hold cues in the recesses, the other end of said arm being bent upon itself and seated in said holder. 115

11. A cue rack comprising a holder having a plurality of spaced recesses to receive the cues, an arm arranged in said holder between said recesses, a roller mounted on said arm and projecting into said recesses to co- 120

125

130

act with adjacent rollers to hold cues in the recesses, the other end of said arm being bent upon itself to abut the rear edge of the holder and having its end seated in said holder.

12. A cue rack comprising a holder having a plurality of spaced recesses to receive the cues and an inclined recess opening at

its rear wall, a spring arm arranged in said holder and having its rear end bent to engage the rear wall of the holder and to be seated in said recess, a roller mounted on said spring arm and projecting into a pair of recesses, and a fastening device engaging said holder and spring arm. ¹⁰
